UNITED STATES PATENT OFFICE.

JOHN J. KENNELLY, OF NEW YORK, N. Y., ASSIGNOR OF ONE-HALF TO
JOHN M. FICKEN, OF SAME PLACE.

MEASURING-FAUCET.

SPECIFICATION forming part of Letters Patent No. 635,256, dated October 17, 1899.

Application filed October 4, 1898. Serial No. 692,610. (No model.)

To all whom it may concern:

Be it known that I, JOHN J. KENNELLY, of the city of New York, borough of Manhattan, in the county of New York and State of New 5 York, have invented a new and Improved Measuring-Faucet, of which the following is a full, clear, and exact description.

My invention relates to an improvement in faucets by which it is possible to measure 10 the amount of liquor drawn and to adjust the same for different amounts, the faucet being automatic in that it shuts off the flow of liquor when the required amount has been drawn.

15 My invention comprises the novel features hereinafter described and claimed.

Reference is to be had to the accompanying drawings, forming a part of this specification, in which similar characters of reference indicate 20 corresponding parts in all the views.

Figure 1 is a side elevation of my faucet with a part thereof in section. Fig. 2 is a top plan view of the same. Fig. 3 is a sectional side elevation similar to Fig. 1, showing 25 the parts in a different position. Fig. 4 is a sectional plan view taken upon the line 4-4 of Fig. 3, and Fig. 5 is a cross-sectional elevation of the weighing-lever with its weight and the registering mechanism.

30 The object of my invention is to produce a faucet which shall be simple and cheap of construction and which may be adjusted so that a definite amount of liquor may be drawn before its mechanism is operated to close the valve. This end is secured by means of a weighing-lever, upon which a vessel is placed, into which the liquor is drawn, and a hand-lever which is used for opening the valve and is engaged by the weighing-lever to hold the 35 valve open until the liquor in the vessel reaches the required weight, when the hand-lever is released and the valve closed.

The stem of the faucet A is of any ordinary construction and is connected with the outer 40 end A' by means of a passage having a valve-seat a, formed in the stem and adapted to be engaged by a valve B, which is normally held

upward against the valve-seat a. The valve is held closed by the pressure of the liquor in the reservoir from which the liquor is being 50 drawn.

The stem B' of the valve B extends upward through a suitable stuffing-box and near its upper end is provided with a slot b. Arms F are supported from the body of the faucet 55 and at their outer ends are provided with a pivot e, upon which the hand-lever E is mounted, which lever is provided with a handle E' upon one arm and has the other arm E² extended through the slot b in the upper 60 end of the valve-stem B'.

The body of the faucet is provided with two A-shaped projections a', located upon opposite sides and adapted to act as fulcrums for the weighing-lever D, which weighing-lever 65 has its outer end provided with a hook d, upon which the vessel J, which is to receive the liquor, may be hung. The lever is forked into two branches D', each of which is provided with a projection d², having a V-shaped 70 notch therein adapted to engage the upper edge of the projection a' upon the valve-body. The end of the lever opposite the one upon which the vessel is to be hung has a counter-weight I mounted thereon, so that it may be 75 slid along the lever.

In ordinary use only two positions of the lever will be required—as, for instance, that required for weighing a pint or a quart of liquid. It is evident, however, that the lever may be adjusted so as to regulate the position of the weight for a number of different amounts. A stop d' is provided on the outer end of each arm D', which limits the motion of the weight in one direction. An 80 arm G' extends rearwardly from the valve-body and is provided with an aperture through which passes a pin G, which rests upon a cross-bar D², forming a part of the lever D, the upper end of said pin engaging a 85 recess e' in the under surface of the arm E² of the hand-lever E.

The weighing-lever D is provided with a catch C, beneath which is a spring C', which

normally holds the catch above the upper surface of said lever. The hand-lever E has a downwardly-projecting lug E³, adapted to engage the catch C when the hand-lever is pulled outward. When the empty vessel J is placed upon the weighing-lever, the weight of said vessel is not sufficient to hold the outer end of said lever down, and consequently the catch C is held in engagement with the lug E³ upon the hand-lever, thus preventing said lever from being swung toward the valve-stem. By reason of the connection of the hand-lever with the valve-stem the valve is depressed and the liquid is permitted to flow through the faucet until the weight of the liquid in the vessel J is sufficient to overcome the influence of the weight I on the lever D, whereupon the outer end of the lever D will swing downward and the weighted end will rise, and this will result in freeing the spring-catch C and the lug E³, thus permitting the lever E to swing toward the valve-stem and cause the valve B to be closed. To insure positive action in this respect, the pin G is employed, and as this pin rests upon the lever D and bears against the under surface of the arm E² of the hand-lever E when the outer end of the lever D swings downward the arm E² of the hand-lever is forced upward. This action may be further secured by placing a spring K about the upper portion of the valve-stem B', said spring bearing against the under surface of the arm E² of the hand-lever and upon the arm G' of the valve-body. The spring K, or one which will accomplish the same result, may be arranged in other ways to act upon the lever E.

A register is provided by means of which the amount of liquid drawn from the supply and delivered by the faucet may be ascertained. This register H is of any suitable character and is made double or in two parts, one for registering the small amounts and the other for registering the large amounts which the faucet is designed to deliver into the vessel J. The two parts of the register are provided with arms h and h', which extend at opposite sides of the center line of the register, and the weight I on the lever D has an arm I² thereon adapted to engage one or the other of the arms h h'. When the weight I is adjusted toward the valve-stem, then as the weighted end of the lever D rises the arm I² of the weight will engage the arm h' of the register and will operate the mechanism which registers small amounts. When the weight I is moved to the end of the lever D, then as the weighted end of the lever D rises the arm I² of the weight will engage the arm h of the register and operate the mechanism which registers large amounts. The arm I² thus engages one or the other of the arms h h' upon the register when the weighted end of the lever D is raised, and a complete record is thus obtained of the amount of liquid delivered by the faucet.

Having thus described my invention, I claim as new and desire to secure by Letters Patent—

1. A measuring-faucet having a valve-operating mechanism extending outside the faucet, a balance or weighing lever adapted to support a vessel to receive the discharge from the faucet, an adjustable weight upon the weighing-lever, a two-part register or counter, each part having an operating-arm, said arms being located at different distances from the pivot of the weighing-lever and adapted to be engaged in turn by the sliding weight when adjusted to its two positions, and a hand-lever connected with the valve-opening means and engaged by the weighing-lever, to hold the valve open until the weighing-lever is depressed by the filling of the vessel. 85

2. A measuring-faucet having a pressure closing-valve, a valve-stem extending outside the faucet, a balance or weighing lever adapted to support a vessel to receive the discharge from the faucet, a hand-lever connected with the valve-stem and engaged by the weighing-lever, to hold the valve open until the weighing-lever is depressed by the filling of the vessel, and a sliding pin between the weighing and hand levers, and acting to raise the latter. 90

3. The combination of a two-part registering apparatus, an arm in connection with each part thereof, a swinging lever, and an adjustable weight on the lever, the weight having an arm movable with the weight so as to place the arm of the weight in position to engage either one of the arms of the registering apparatus. 100

4. The combination of a two-part registering apparatus, an arm in connection with each part thereof, and a member mounted to move relatively to the registering apparatus and having a part movable to engage either one of the arms of the registering apparatus. 110

5. In a measuring-faucet, the combination with a faucet-stem provided with a valve-seat and a valve mounted on the seat, of a valve-stem attached to the valve and projecting upward from the faucet-stem, a weighing-lever mounted on the faucet-stem and adapted to carry the vessel to be filled, a sliding pin engaged by the weighing-lever, a hand-lever mounted on the faucet and having one arm engaged with the valve-stem 120 and with the sliding pin, and a catch serving temporarily to hold the hand-lever and the weighing-lever in engagement with each other, whereby to keep the valve open. 115

6. In a measuring-faucet, the combination with a faucet-stem having a valve-seat and a valve working on the seat, of a valve-stem attached to the valve and projecting upward through the faucet-stem, an arm mounted rigidly on the faucet, a hand-lever fulcrumed on the arm, one arm of the hand-lever projecting through an opening in the upper por- 125 130

tion of the valve-stem, a weighing-lever mounted on the faucet, a sliding pin carried on the faucet and engaged by the weighing-lever and by the said arm of the hand-lever, 5 a catch serving to hold the other arm of the hand-lever temporarily engaged with the weighing-lever to keep the valve open, and a spring bearing between the first-named arm

of the hand-lever and a stationary portion of the faucet, the spring serving to throw the valve-stem with its valve into closed position.
